(57) **CLAIM**

The ornamental design for an exterior unit for an air conditioner, as shown and described.

DESCRIPTION

FIG. 1 is a front, top and left side perspective view of an exterior unit for an air conditioner, showing our new design; FIG. 2 is a front elevational view thereof; FIG. 3 is a rear elevational view thereof; FIG. 4 is a top plan view thereof; FIG. 5 is a bottom plan view thereof; FIG. 6 is a left side elevational view thereof; FIG. 7 is a right side elevational view thereof; and, FIG. 8 is an enlarged cross-sectional view thereof, taken along line 8—8 of FIG. 2.

The broken-line disclosure in the views is for illustrative purposes only and forms no part of the claimed design.
